UNITED STATES PATENT OFFICE.

RHEUBEN W. BAHRE, OF DUQUOIN, ILLINOIS.

COTTER-PIN-EXTRACTING TOOL.

1,316,409.

Specification of Letters Patent. Patented Sept. 16, 1919.

Application filed July 15, 1918. Serial No. 244,981.

To all whom it may concern:

Be it known that I, RHEUBEN W. BAHRE, a citizen of the United States, residing at Duquoin, in the county of Perry and State 5 of Illinois, have invented certain new and useful Improvements in Cotter-Pin-Extracting Tools, of which the following is a specification.

This invention relates generally to extracting tools, and particularly to tools for extracting cotter pins, having for its primary object to generally simplify and improve the construction and operation of devices of this character as well as to increase 15 their efficiency.

A further object of the invention is to provide a cotter pin extracting tool which may be manufactured at exceedingly low cost, and which is constructed in such manner as to provide means for straightening the pin prior to the extracting operation.

With these objects in view, together with others which will appear as the description proceeds, the invention resides in the novel 25 formation, combination and arrangement of parts, all as will be described more fully hereinafter, illustrated in the drawings, and particularly pointed out in the claim.

In the drawings:—

30 Figure 1 is a perspective view of a cotter pin extracting tool constructed in accordance with the invention, and

Fig. 2 is a side elevation of the improved tool.

35 Referring now more particularly to the drawing, 3 and 4 indicate respectively crossed handle members, the same being pivoted together inwardly from their ends as at 5.

40 The members 3 and 4 adjacent their point of connection are provided with jaws 6 and 7 whose faces abut each other throughout their lengths when the tool is closed.

The free end of the jaw 7 on the member 45 3 is provided with a table or anvil 8, having an aperture 9 therein to receive a bill or wedge 10 at the free end of the jaw 6 on the handle 4.

When the handle members 3 and 4 are 50 grasped and moved toward each other, the jaw portions 6 and 7 move correspondingly and the wedge or bill 10 moves into the aperture 9 in anvil 8. It will be observed

that the bill 10 is of substantially pyramidal form so that the said member entering between the leg portions of a cotter pin will cause the said portions to move apart.

When it is desired to use the tool in applying a cotter pin, the straight pin is passed through the opening to receive the same, 60 whereupon the tool is applied to the free end of the leg portions of the pin by placing the anvil 8 directly beneath the same. Closing of the jaws then causes the bill or wedge 10 to move downwardly between the leg 65 portions thereof. Continued inward pressure applied to the handles of the tool causes the wedge to move further downwardly, whereupon the leg members are separated. In removing a cotter pin, the 70 divergent leg portions thereof are grasped between the jaw faces 6 and 7, and the handle portions are then moved together. This movement causes the jaws to force the leg portions together or in other words 75 straighten the pin. The bill 10 may then be inserted through the eye of the cotter pin to facilitate withdrawal of the same.

Having thus fully described my invention, what I claim as new and desire to secure 80 by Letters Patent is:

In a device of the character described, the combination of a pair of crossed handle members pivotally connected together to form jaws immediately in front of the pivot 85 thereof, reduced extensions projecting beyond the outer ends of the jaws, one of the extensions terminating in an apertured flat anvil and the other terminating in an angular wedge shaped bill in position to move 90 through the aperture of the anvil as the handle members are swung together, said jaws having flat abutting surfaces spaced inwardly toward each other at a considerable distance from the surfaces of the extensions, whereby articles may be gripped by said jaws without injury to said articles and without interference from said extensions, as and for the purposes set forth.

In testimony whereof I affix my signature 100 in presence of two witnesses.

RHEUBEN W. BAHRE.
